DESIGN FOR A TRUCK TANK

Ralph B. Ziegler, Philadelphia, Pa., assignor to Quaker City Iron Works, Philadelphia, Pa., a corporation of Pennsylvania

Application January 24, 1944, Serial No. 112,317

Term of patent 7 years

(Cl. D14—3)

To all whom it may concern:

Be it known that I, Ralph B. Ziegler, a citizen of the United States of America, residing at Philadelphia, in the county of Philadelphia and State of Pennsylvania, have invented a new, original, and ornamental Design for a Truck Tank, of which the following is a specification, reference being had to the accompanying drawing, forming part thereof.

In the drawing:

Fig. 1 is a side elevational view of a truck tank, showing my new design.

Fig. 2 shows the tank in top plan.

Figs. 3 and 4 are elevations of the opposite ends of the tank.

I claim:

The ornamental design for a truck tank, as shown.

RALPH B. ZIEGLER.
